Primary Examiner — Khawaja Anwar*Assistant Examiner* — Megan Tiana Rakos(74) *Attorney, Agent, or Firm* — Spencer Fane LLP;
Steven J. Laureanti(57) **CLAIM**

The ornamental design for a music visualization speaker, as shown and described.

DESCRIPTION

FIG. 1 is a perspective view of the present invention; FIG. 2 is a front view of the present invention; FIG. 3 is a back view of the present invention; FIG. 4 is a right side view of the present invention; FIG. 5 is a left side view of the present invention; FIG. 6 is a top view of the present invention; FIG. 7 is a bottom view of the present invention; and, FIG. 8 is a rear perspective view of the present invention. The broken lines in the figures immediately adjacent the solid lines represent the bounds of the claim, and the broken lines and the area within the broken lines represent unclaimed portions of the present invention. None of the broken lines form a part of the claimed design.
